UNITED STATES PATENT OFFICE.

AUGUST LASANCE, OF CINCINNATI, OHIO.

TRIMMING-MACHINE.

No. 829,111.

Specification of Letters Patent.

Patented Aug. 21, 1906.

Application filed September 18, 1905. Serial No. 279,029.

To all whom it may concern.

Be it known that I, AUGUST LASANCE, a citizen of the United States, and a resident of Cincinnati, in the county of Hamilton and State of Ohio, have invented a certain new and useful Improvement in Trimming-Machines, of which the following is a full, clear, and exact description, reference being had to the accompanying drawings, which form a part of my specification.

My invention relates to a machine for trimming the edges of wooden boxes, and is intended more especially for the purpose of trimming the corners and edges of wooden boxes whose sides are dovetailed into each other, eliminating the use of screws or nails, the object being to take off the sharp and rough edges and corners, and thus give the box a neater appearance.

20 A further object is to provide means for taking off any portions of the top or bottom that may extend beyond the sides of the box proper, and thus diminishing the likelihood of the box being broken by reason of jars or the 25 contacting of the extended parts of the top or bottom of the box with other objects, as is likely to be the case when the filled boxes are shipped from place to place.

In the drawings, Figure 1 is a top plan 30 view of my improved machine. Fig. 2 is an elevation taken from the rear side of the machine with a portion broken away and shown in section, the same being taken along the line 2 2 of Fig. 1. Fig. 3 is a side elevation of 35 my improved machine more especially intended to show the mechanism for regulating the throw of the foot-treadle. Fig. 4 is a longitudinal sectional view taken on the line 4 4 of Fig. 1.

40 Like letters of reference indicate identical parts in the respective figures.

A A are the side uprights or frame of the machine, which are suitably supported and united together by the cross-bars B B and C 45 C. D D' constitute a sectional table for the box to be operated upon and are supported on the bed-plate D''. The tables D D' are provided with pivotal bearings, as at a, Fig. 4, so that they may be tilted up at one end 50 for a purpose to be hereinafter set forth. E is a revolute shaft which extends transversely of the machine and is provided with suitable bearings b b', Figs. 1 and 2, and is provided at its free end with the pulley F, 55 which receives a belt from a power-shaft. Suitably mounted on this revolute shaft E

and at proper points beneath the sections of the table D D' are the cutters or knives G G'. These cutters or knives G G' comprise a series of bits which are mounted on blocks, secured to opposite faces of the blocks, and at right angles to each other in a well-known manner, as can more clearly be seen in Fig. 4, and the blocks are secured to the shaft E. The bits c are constructed with a hollowed-out or concaved cutting edge and are the cutters whereby the edges of the box are trimmed or rounded off. The shape of the edge of the bits c can be more clearly seen in Figs. 1 and 2 and 4. Mounted to a side of the boxing to which all of the cutters are secured are the bits d, and which are so secured as to extend slightly above the circumference of the circle described by the cutting edge of the bits c, so that they may be brought into play or in contact with the box to be operated upon when it is not desired to have the edge trimming or rounding bits c to operate on the box. The purpose of these bits or knives will be hereinafter set forth. The extent to which the bits d extend beyond the bits c can be seen in Figs. 2 and 4. The sectional table D D' is of course provided with slots or cut-out portions, through which the knives extend when the table is in its normal 85 position. I provide the two sets of the cutters or knives G and G' so that opposite edges of the box may be trimmed or rounded at the same time.

In order that boxes of different widths 90 may be trimmed, it is necessary to have at least one set of the cutters and one of the sections of the table adjustably mounted so that they may be moved transversely. I therefore provide the shaft E with a slot and secure the cutter-head G to it by a key connection, so that the cutter-head may be slid transversely of the shaft when occasion requires. Of course it is also necessary that the table D be adapted to move in or out toward or from the center of the machine.

I have shown the table D' as provided with a sliding pin connection, as at k, (see Fig. 1,) with the frame of the machine. The pins k take through the frame A of the machine and into the table D'. The pins k are provided with springs l, so as to hold the table-section D' in its normal position, but yet permit the table D' having a slight give for any irregularity or variation in a given-sized box, it being understood that the table D has at that time been adjusted to the particular-

sized box that is being trimmed, so that should a particular box vary slightly in size the table D', together with the cutter-head corresponding therewith, may yield to the variation or irregularity. For this reason I provide the box or casing to which the cutters of the cutter-head G' are secured with an extension or collar m, the collar being provided with a groove m', as seen in Fig. 2. Taking into the groove m' of this collar m is an arm n, (see Fig. 1,) which is secured permanently to the table D'. It will be seen that the arm n, which may either take around the collar m in the groove m' or be made bifurcated, so as to take to either side of the collar, as may be desired, will move the cutter-head G' with the table D' whenever the latter is moved by reason of any slight irregularity or difference in a particular or given sized box to which the machine is set. The cutter-head G' is keyed to the shaft E by the set-screw or key s, which takes into the slot t in the shaft E, as can be seen in Fig. 2. The cutter-head G' is of course connected in this manner to the shaft E, so that it may move along the shaft E whenever the sectional table D' yields by reason of a slight modification or irregularity in the particular-sized box for which the machine is set.

The tables D D' are provided with guides f g, the purpose of the guides g being to hold the box slightly above the tables D D', while guides f are for the purpose of retaining the box in its proper horizontal path and directly at right angles to the axes of the cutters. These guides f and g may be strips of metal bolted onto the tables D D', as can more readily be seen in Figs. 1 and 4, the guides f being bolted onto the upward extension of the angularly-formed tables D D'.

H H are yokes which are connected by bolts h to the tables D D'. Connected with the yokes H in any suitable manner are the rods J J, which have pivotal connection with the shaft or transverse rod K, which latter has its bearing in the links L, which are keyed to the shaft M, which has its bearings in the frame A of the machine. Secured to this loosely-mounted shaft M in any suitable manner is the foot-treadle N, which extends forward to the front of the machine. It will be seen that by depressing the foot-lever N the shaft M will be rotated, thereby throwing the links L upward, which will raise the transverse rod K, and with it the rods J J, whereby the rear ends of the sectional table D D' will be thrown upward. The sectional table being pivotally connected to the frame of the machine at a will be at an incline when foot-lever N is depressed, thus raising it sufficiently to bring the upper surface above the cutting edge of the bits or cutters c.

In order that the throw or elevation of the table by the foot-treadle N may be regu-

lated, I provide the bifurcated arm O, which is properly keyed to the shaft M, as can be seen in Fig. 3, the bifurcations extending above and beneath the cross-bar of the frame A. These bifurcated ends may be provided with set-screws, which may be set so as to still further control or regulate the rotation of the shaft M by the foot-treadle N. The purpose of this table-tilting mechanism is to permit of the trimming off of any extending or overlapping portions of the lid or bottom of a box, which is done by the straight or shearing cutters d, which, as before stated, extend above the cutting edge of the cutters e. It is understood that the cutters d are simply intended to trim off any protruding portions of the top or lid of a box, and when this is done the tables D D', together with the box operated upon, must be tilted above the cutting edge of the rounding-bits e; otherwise they would produce or cut a concaved groove in the lid near its edge.

I have illustrated and described what I believe to be the preferable form of machine; but it will be readily understood that the machine may be altered in a number of minor details, and instead of using the throw-regulating mechanism for the foot-treadle described other mechanism may be employed and differently-constructed bits or cutters may be used instead of those I have shown, and therefore I do not wish to be understood as limiting myself to the precise construction herein set forth; but

What I claim as my invention, and wish to secure by Letters Patent, is—

1. A trimming-machine for wooden boxes and the like, comprising a sectional table provided with guideways and being pivotally mounted at its one end on the frame of the machine, each section provided with a slot, a revolute shaft, with two sets of cutter-heads mounted therein, each set comprising a rounding-bit and a shearing-bit, means whereby said sectional table may be raised to permit of the action of but one portion of said cutter-heads.

2. A machine for trimming the edges of wooden boxes and the like comprising a frame, a revolute shaft suitably mounted therein, a set of cutter-heads comprising concave or rounding bits and straight or shearing bits, the cutting edge of the latter arranged to extend slightly beyond the cutting edge of the former and to lie in a different vertical plane, a sectional table having pivotal connection at its one end with the frame of the machine and provided with slots through which the cutter-heads are adapted to extend, guideways provided on the table-sections whereby the relation to the cutter-heads of the box to be trimmed is maintained, one of the table-sections and its corresponding cutter-head adjustably mounted, mechan-

ism having controllable connection with the one end of said table-sections whereby their relation to the cutter-heads may be altered, substantially as shown and described.

- 5 3. In a trimming-machine for wooden boxes and the like, the combination of a pivotally-mounted sectional table provided with guideways, one of said sections being yieldingly mounted, and the other section transversely adjustable, a revolute shaft provided with two cutter-heads, each head comprising a set of cutting-bits and a set of shearing-bits, with means whereby the table may be arranged to permit of the action of but 15 one set of bits on the box being trimmed.
4. A trimming-machine for wooden boxes and the like, comprising a sectional table provided with guideways, a slot in each of said sections, a revolute shaft provided with 20 two cutter-heads, each cutter-head comprising a set of rounding-bits and a set of shearing-bits adapted to extend up through the slots in the table-sections, one of said table-sections and its respective cutter-head being 25 yieldingly mounted on said machine, and the other table-section and its respective cutter-head being mounted to permit of transverse adjustment, substantially as shown and described.
- 30 5. A trimming-machine for wooden boxes and the like comprising a sectional table provided with guideways, a slot in each of said sections, a revolute shaft provided with two cutter-heads, each cutter-head comprising 35 a set of rounding-bits and a set of shearing-bits, one of said table-sections and its respective cutter-heads being yieldingly mounted on the frame of the machine, and the other table-section and its respective cutter-head 40 being transversely adjustable, and means whereby the table-sections may be tilted at

their one end to bring their surface above the cutting edge of the bits, substantially as shown and for the purpose described.

6. A trimming-machine for wooden boxes 45 and the like, comprising a sectional table, guideways adjustably secured to said sections, a revolute shaft provided with two cutter-heads each comprising a set of cutting-bits and a set of shearing-bits, one of said table-sections and its respective cutter-head being yieldingly mounted, means intermediate of said table-section and its cutter-head whereby their relation to each other is constantly maintained, the other table-section 50 and its cutter-head being adjustable transversely of the machine, and means whereby the table-sections may be tilted at their one end and their horizontal relation to the cutter-heads altered, substantially as shown and 55 for the purpose described.

7. A trimming-machine for wooden boxes and the like, comprising a sectional table provided with guideways, a slot in each of said sections, a revolute shaft provided with two 60 cutter-heads, each cutter-head comprising a set of rounding-bits and a set of shearing-bits adapted to extend up through the slots in the table-sections, one of said table-sections and its respective cutter-heads being 65 yieldingly mounted on the frame of the machine and the other table-section and its respective cutter-head being transversely adjustable, means whereby the table-sections may be tilted at their one end, and mechanism 70 whereby the movement of the tilting means may be regulated, substantially as shown, and for the purpose described.

AUGUST LASANCE.
